UNITED STATES PATENT OFFICE.

EDWIN S. VOTEY, OF NEW YORK, N. Y., ASSIGNOR TO THE AEOLIAN COMPANY, OF NEW YORK, N. Y., A CORPORATION OF NEW YORK.

PORTABLE PLAYER FOR MUSICAL INSTRUMENTS.

No. 824,050.

Specification of Letters Patent.

Patented June 19, 1906.

Application filed June 22, 1903. Serial No. 162,506.

To all whom it may concern:

Be it known that I, EDWIN S. VOTEY, a citizen of the United States, residing in the borough of Manhattan, city, county, and State of New York, (post-office address, Aeolian Hall, No. 362 Fifth avenue, New York city,) have invented certain new and useful Improvements in Portable Players for Musical Instruments, of which invention the following is a specification, accompanied by drawings, which illustrate a preferred form thereof.

An object of the invention is the provision of means to permit the arrangement of the mechanism for actuating the keys under the keyboard of a musical instrument in that class of mechanically-played musical instruments in which a tracker and music and take-up rolls are in playing position located in front of the keyboard for convenience of manipulation.

A further object is to mount the tracker and music and take-up rolls on an attachment so that they may be moved from playing position either for clearing the keyboard of any obstruction when the piano or organ is to be played by hand or for shipment of the instrument.

The invention is described, and illustrated in the accompanying drawings, as being applied to certain known and used forms of mechanism, and the improvements constituting the present invention are incorporated in the claims.

In the accompanying two sheets of drawings, Figure 1 is a sectional front elevation of a mechanical musical instrument, the casing being shown in section and a keyboard being also shown broken away at each end. Fig. 2 is a transverse section thereof viewed from the right of Fig. 1. Fig. 3 is a detail sectional view, on a larger scale, showing the frame for supporting the tracker and music and take-up rolls, parts of these being also shown, as well as driving mechanism and a means for reversing the direction of movement of the music-sheet. Fig. 4 is a section on line 4-4 of Fig. 3. Fig. 5 is a section on the line 5-5 of Fig. 3, and Fig. 6 is an enlarged detail of the pneumatic playing mechanism.

It is old and well known in many forms of mechanical musical instruments to control primary pneumatics by a tracker-board and

its connections, over which tracker-board a perforated music-sheet travels, and to cause 55 primary pneumatics to operate secondary pneumatics, which in turn control the pneumatically-operated mechanism for effectuating the playing. It is also old and well known to provide in connection with such a 60 tracker-board a music-roll and a take-up roll for operating the music-sheet either to unwind it from the music-roll slowly or to unwind it rapidly from the take-up roll, the reverse movement being accomplished by a 65 suitable reversing-lever.

In the drawings I have selected for illustration a well-known form of instrument, and it is not, therefore, necessary to describe in detail the old and well-known parts thereof. 70

The essence of the present invention consists in mounting the tracker so as to move with the music-roll and the take-up rolls when they are moved to a position for playing or to position below the keyboard, thereby 75 leaving the keyboard free for the playing of the instrument by hand.

In the preferred way of carrying out the invention the usual type of tracker and music and take-up rolls is provided, with the exception that they are movable from operative position for automatic playing to non-operative position to permit playing by hand.

The following-described construction is the preferred form of the present invention: A 85 portable case *a* is provided, which in use is located under the keyboard *b*, and which requires for this reason that the tracker, music, and take-up rolls be mounted so that they may be moved into position for automatic 90 playing or into position within the case when the automatic portion of the mechanism is not to be used. The case has pivoted thereto at *a'* a suitable supporting-frame *c*, which supports a tracker *d*, which by means of 95 flexible connections, such as tubes *d'*, is connected with the primary pneumatics, such as *e*, which actuate valves *e'*, that in turn control secondary pneumatics *f* for actuating the valves *f'*, which are in turn arranged to 100 control the pneumatic motors *f''*. These pneumatic devices are simply shown here by way of example of pneumatic devices which may be used to actuate the keys *b* or any other part of the piano-action through any 105 suitable connection with the motors *f''*. As

shown, the actuating mechanism in portable case *a* may be connected with levers *b'*, extending forwardly from the musical instrument, by resting the ends of rearwardly-projecting levers *b*³ in the upper part of case *a* upon the ends of levers *b'*. The shaft *a'*, on which the frame *c* is pivoted, is located at the forward upper corner of the case *a* and constitutes a power-transmitting shaft, whereby motion is communicated from the motor or engine *g* to the music-roll *h* and take-up roll *h'*.

The take-up roll *h'* is driven by a shaft *i*, which carries a gear-wheel *i'* and is journaled in the wall of a box or casing *j*, located at one side of the supporting-frame *c*. This gear-wheel meshes with a pinion *k*, arranged on a shaft *k'*, journaled in the casing *j*, said shaft also carrying a sprocket-wheel *k*². On the shaft *k'*, between the pinion *k* and a clutch member *l*, also on the shaft, is a smaller sprocket-wheel *k*³, said clutch being adapted by a feather-and-groove connection (not necessary to be shown) to couple the sprocket-wheel *k*³ to drive the sprocket *k*². As shown, the pinion *k*, sprocket-wheel *k*³, and clutch member *l* are made in the form of a sleeve which slides on the shaft, in which case when the pin *l'* on clutch member *l* is engaged with the pin *l*² at the side of the sprocket-wheel *k*² the pinion *k* is disengaged from the gear-wheel *i'*, or vice versa. The power-transmitting shaft *a'* is provided with a sprocket-wheel *m*, over which is trained a sprocket-chain *m'*, (indicated by dotted lines,) also trained over the sprocket-wheel *k*³, before referred to. Also mounted on the shaft *a'* is a sprocket-wheel *o*, Fig. 1, driven from a suitable sprocket-chain *o'*, trained over sprocket-wheel *o*² on motor-shaft *g'* for the purpose of rotating the shaft *a'*. A reversing-lever *n* is provided at *n'* in the box or casing *j*. The lever *n* is provided with a button *n*², which projects through the box or casing *j* for the manipulation of said lever *n*, which, acting on the clutch member *l*, serves as a reversing-lever for the purpose presently to appear. The sprocket-wheel *k*², before referred to, has trained thereover a sprocket-chain *p*, which is also trained over a sprocket-wheel *p*², constructed at that end which projects outside the casing *j* to serve in well-known manner as a coupling to receive the shaft of the music-roll *h*. This is a convenient point to describe the operation of the mechanism for transmitting motion to the rolls to cause the music-sheet to travel over the tracker. When the mechanical musical instrument is in operation for automatic playing, the reversing-lever *n* is in the position shown in full lines in Fig. 3, the gear-wheel *i'* being then driven from the sprocket-chain drive *m* *m'* *k*³, in consequence of which rotary motion

is imparted to the lower take-up roll *h'* to 65 wind the music-sheet thereon and to unwind it from the music-roll at a slow rate of speed. After the piece of music has been played the music-sheet is rewound on the music-roll by reversing the direction of rotation of the rolls, 70 this being effectuated by shifting the lever *n* so as to engage the clutch *l* and the clutch *l'* at one side of the sprocket-wheel *k*². The sprocket-chain *p* will then be driven to impart rotary motion directly to the music-roll 75 from its shaft, thereby rewinding the music-sheet onto said roll.

The supporting-frame *c* for the music and take-up rolls and the tracker may be moved into the position shown in full lines in Figs. 1 80 and 2, so as to be located in position for manipulation in front of the keyboard *b*, or in the position shown in dotted lines in Fig. 2, in which position it is moved into a recess or receptacle *q* in front of the case *a*. This recess is of such size as to receive the entire supporting-frame and parts supported thereby and makes it possible to store the said frame and supported parts in the case for transportation or for obtaining free access to 90 the keyboard *b* for manual playing.

A tempo-slide *r*, provided with a pointer to set opposite a scale *r'*, moves in a slot *r*² in one wall of the box or casing *j*, it being mounted upon a bent-wire sliding piece *r*², which is 95 guided in the box or casing *j*. The wire sliding piece *r*² is provided at that side of the supporting-frame which, when the same is moved up into the position shown in Fig. 1, constitutes the back of the frame, with a cranked finger *s*, which is, by means of a connecting-rod *s'*, connected with the valve *s*³ of the tempo mechanism. (Not necessary to be illustrated in detail.)

The swinging supporting-frame for the 105 tracker, music, and take-up rolls may be fixed in position (shown in full lines in Fig. 2) for automatic playing by a special catch; but this is not necessary, as when the frame is raised to such position it passes the center of 110 gravity and rests against a superposed portion—as, for instance, the keybed or projecting part of that part of a piano underlying the keyboard. The flexible tubes *d*', leading to the tracker, are of sufficient length so that 115 no breaking strain will be exerted thereon during the raising or lowering of the swinging supporting-frame.

The bellows *t* of the pneumatic playing 120 mechanism are operated in well-known manner from treadles *t*', these treadles being pivoted, so that they may be moved into the position shown in dotted lines in Fig. 2 when out of use. The compartment in which the treadles are arranged is closed by means of a 125 door *u*, hinged to a strip *u'*, that is guided in suitable ways at the sides of the compartment, but which in Fig. 2 is shown in raised

position for obtaining access to the treadles t' . When the door u is moved up, as shown, it will be located in front of and will close the recess q , which receives the movable support c .

5 Between the treadles t' are located extension-pedals v of the piano-pedals w . The extension-pedals v are formed as crank-arms of rock-shafts v' , which are journaled in suitable bearings at the base of the apparatus-case a . The rear ends of the rock-shafts v' are provided with hooks w' , which engage over the ends of the pedals w , that extend through the back of the case a .

15 The operation of the entire apparatus when in the form of the invention shown in the drawings is as follows: The case a is moved under the projecting keyboard portion of the piano, so that the pivot a' will be arranged properly relatively to the keyboard. The sliding door u is then raised and the treadles t' pulled out so that their feet will rest upon the floor to permit of the oscillation thereof and the operation of the bellows.

25 The movable support c is moved from the dotted-line position in its recess q either before the door is raised or afterward into full-line position shown in Figs. 1 and 2, the said support, with the supported parts—as the tracker, music, and take-up rolls—being arranged in front of the forward ends of the keys b in convenient position for manipulation by the operator of the apparatus. The music-roll, if not already in position, is then

35 placed in position above the tracker and the music-sheet passed across the tracker and attached to the take-up roll. The apparatus is now in playing order, and it is only necessary to operate the treadles to automatically perform the music which is cut in the music-sheet. When it is desired to manually perform on the piano or organ, the treadles t are moved into the case a , the door u moved down, and the movable support c swung down

45 into the dotted-line position shown in Fig. 2. The performer now plays, as usual, upon the keys b and obtains the desired expression by the actuation of the extension-pedals V . This is done without removing the case a , 50 with its contained parts, from underneath the keyboard.

Having thus described my invention, and without limiting myself to details, what I claim as new therein, and desire to secure by Letters Patent, is—

1. The combination of the keyboard of a musical instrument, a case separate from the instrument and located under the keyboard, actuating mechanism connected with that of the instrument, a tracker, operating connections leading from the tracker to said mechanism, for the respective notes, and a swinging support on the case on which the tracker is mounted to permit its movement upwardly

in front of the keyboard or downwardly below the same, substantially as set forth. 65

2. The combination of the keyboard of a musical instrument, a case separate from the instrument and located under the keyboard, actuating mechanism connected with that of the instrument, a tracker, operating connections leading from the tracker to said mechanism, for the respective notes, music and take-up rolls for moving a music-sheet across said tracker, and a swinging support on the case 75 on which the tracker is mounted to permit its movement upwardly in front of the keyboard, or downwardly below the same, substantially as set forth.

3. The combination of a keyboard of a musical instrument, a case separate from the instrument and located under the keyboard, actuating mechanism connected with that of the instrument, a tracker, operating connections leading from the tracker to said mechanism, for the respective notes, a movable support on said case, and music and take-up rolls mounted on said support for moving a music-sheet across the tracker, said support being adapted to be moved up in front of the keyboard, or down below the same, substantially 85 as set forth.

4. The combination of a keyboard of a musical instrument, of a case below the keyboard provided with a recess in front, actuating mechanism located in the case and connected with that of the instrument, a tracker, operating connections leading from the tracker to said mechanism, for the respective notes, and a movable support on said case on which the tracker is mounted, said support being movable upwardly in front of the keyboard or downwardly into the said recess, for permitting mechanical and manual playing, respectively, substantially as set forth. 95

5. The combination of a keyboard of a musical instrument, of a case below the keyboard provided with a recess in front, actuating mechanism located in the case and connected with that of the instrument, a tracker, operating connections leading from the tracker to said mechanism, for the respective notes, a take-up roll, and a movable support on said case on which the take-up roll is 100 mounted, said support being movable upwardly in front of the keyboard or down into the said recess, for permitting mechanical and manual playing, respectively, substantially as set forth. 110

6. The combination of a keyboard of a musical instrument, of a case below the keyboard provided with a recess in front, actuating mechanism located in the case and connected with that of the instrument, a tracker, 115 operating connections leading from the tracker to said mechanism, for the respective notes, a music-roll, and a movable support

on said case on which the music-roll is mounted, said support being movable upwardly in front of the keyboard or down into the said recess, for permitting mechanical and manual playing, respectively, substantially as set forth.

7. In a portable player for musical instruments, the combination of a case detachable from and applicable to such an instrument provided with a front recess and in which the operative parts of the player are contained, and a support for a tracker, music-roll and take-up pivoted at the top of the case and movable into said recess, substantially as set forth.

8. In a portable player for musical instruments, the combination of a case detachable from and applicable to such an instrument provided with a front recess and in which the operative parts of the player are contained, and a support for a take-up roll pivoted at the top of the case and movable into said recess, substantially as set forth.

9. The combination with the keyboard and pedals of a manually-played musical instrument, of a portable case located under the keyboard, actuating mechanism in the case and connected with that of the instrument, a tracker, operating connections leading from the tracker to said mechanism, for the respective notes, a movable support on said case on which the tracker is mounted to permit its movement in front of the keyboard or down into the case, and extension-pedals located at the front of the said case and connected with the main pedals of the instrument, substantially for the purposes set forth.

10. A mechanical player for keyboard musical instruments adapted to be positioned beneath the keyboard of such instrument and integrally removable from such position, having means for carrying and operating a controlling music-sheet, and a support on which said sheet-carrying means is movably mounted to occupy alternatively an operative position above such keyboard, or a non-operative position beneath such keyboard.

11. A mechanical player for keyboard mu-

sical instruments including a casing adapted to be positioned beneath the keyboard of such instrument and integrally removable from such position, power-supplying means for winding a music-sheet in said casing, means carrying rotatable rolls for said music-sheet, and a support on which said roll-carrying means is movably mounted to occupy alternatively an operative position above such keyboard, or a non-operative position beneath such keyboard.

12. A mechanical player for keyboard musical instruments including a casing adapted to be positioned beneath the keyboard of such instrument and integrally removable from such position, a movable front portion on said casing, power-supplying means for winding a music-sheet in said casing, means carrying rotatable rolls for such music-sheets, and a support on which said roll-carrying means is movably mounted to occupy alternatively an operative position above said keyboard, or a non-operative position beneath said keyboard and behind said front portion.

13. In combination with a musical instrument having a keyboard extending forwardly of its lower front portion and a plurality of means beneath said keyboard for separately operating its sound-producing devices, a mechanical player adapted to be positioned beneath said keyboard and integrally removable from said position, having means for co-operating with said first-named means to sound said instrument, means for carrying and operating a controlling music-sheet, and a support on which said sheet-carrying means is movably mounted to occupy alternatively an operative position above said keyboard, or a non-operative position beneath said keyboard.

In testimony whereof I have signed this specification in the presence of two subscribing witnesses:
